(57) **CLAIM**

The ornamental design for a hand grip, as shown and described.

DESCRIPTION

FIG. 1 is a top front perspective view of a hand grip, showing my new design;

FIG. 2 is a top rear perspective view thereof, with stippling for illustrating adhesive;

FIG. 3 is a front elevation view thereof;

FIG. 4 is a rear elevation view thereof, with stippling for illustrating adhesive;

FIG. 5 is a right elevation view thereof;

FIG. 6 is a left elevation view thereof;

FIG. 7 is a top plan view thereof;

FIG. 8 is a bottom plan view thereof; and,

FIG. 9 is a front elevation view thereof, shown in use. The broken lines shown in the drawings depict a portion of the hand grip that forms no part of the claimed design.

1 Claim, 6 Drawing Sheets
